Primary Examiner—T. Chase Nelson*Assistant Examiner*—Michelle E Wilson(74) *Attorney, Agent, or Firm*—Leydig, Voit & Mayer, Ltd.(57) **CLAIM**

The ornamental design for a medical transdermal patch, as shown and described.

DESCRIPTION

FIG. 1 is a front view of a medical transdermal patch of the present invention, also showing portion 7—7 of the medical transdermal patch.

FIG. 2 is a rear view of the medical transdermal patch of FIG. 1.

FIG. 3 is a top plan view of the medical transdermal patch of FIG. 1.

FIG. 4 is a bottom view of the medical transdermal patch of FIG. 1.

FIG. 5 is a right side view of the medical transdermal patch of FIG. 1.

FIG. 6 is a left side view of the medical transdermal patch of FIG. 1.

FIG. 7 is an enlarged perspective view of the 7—7 portion of the medical transdermal patch of FIG. 1 showing shading; and,

FIG. 8 is a reference view of the medical transdermal patch of FIG. 1 in preparation for use.

The broken line showing of the environment is for illustrative purpose only and forms no part of the claimed design.
